DESIGN FOR A LOCKET

Harland L. Mossman, Jr., Omaha, Nebr.

Applicaiton October 5, 1935, Serial No. 58,840

Term of patent 7 years

To all whom it may concern:

Be it known that I, Harland L. Mossman, Jr., a citizen of the United States of America, residing at the city of Omaha, in the county of Douglas and State of Nebraska, have invented a new, original, and ornamental Design for a Locket, of which the following is a specification, reference being had to the accompanying drawing, forming a part thereof.

In the drawing, Fig. 1 is a front view of the locket, and Fig. 2 is a side view of the same. Fig. 3 is a rear view of the locket.

I claim:

The ornamental design for a locket as shown. In testimony whereof, I affix my signature.

HARLAND L. MOSSMAN, JR.
